UNITED STATES PATENT OFFICE.

WALTER W. BRADBURY, OF LAWRENCE, MASSACHUSETTS, ASSIGNOR TO THE STANLEY COMPANY, OF BOSTON, MASSACHUSETTS, A CORPORATION OF MASSACHUSETTS.

MACHINE FOR APPLYING LABELS.

No. 860,629.

Specification of Letters Patent.

Patented July 23, 1907.

Application filed December 28, 1905. Serial No. 293,608.

To all whom it may concern:

Be it known that I, WALTER W. BRADBURY, a citizen of the United States, residing at Lawrence, in the county of Essex and State of Massachusetts, have invented an improvement in Machines for Applying Labels, of which the following description, in connection with the accompanying drawings, is a specification, like letters on the drawings representing like parts.

This invention relates to the production of a machine for applying labels to bottles, cans and other articles, the invention being shown as exemplified in connection with bottles.

One part of this invention refers to novel means for presenting and delivering the labels one at a time, also to novel means for applying gum or paste to the labels, also in a novel label sustaining fork and means for operating the same; also to novel jaws and means for controlling the movement of the same for wiping the labels on to the bottles or other articles and also to a novel dating stamp.

Other features of the invention will be hereinafter described and pointed out in the claims at the end of the specification.

Figure 1 in front elevation represents my novel machine; Fig. 2 is a detail showing the label wiper in operative position; Fig. 3 is a longitudinal section through the paste trough its roller and the top of the label box, the section being an irregular section below the top of the label box to show the means for actuating the lever for moving the paste box and label box in opposition; Fig. 4 is a plan view of the machine shown in Fig. 1; Fig. 5 is a detail showing one end of the label holder and the framework in which it slides, said figure also showing the stud 10 to be described.

The frame work A, of suitable shape to sustain the working parts has bearings in which rotates the shaft A' having a pulley A² shown as adapted to be driven by a belt. The shaft A' has a disk A³ provided at its left hand side, see Fig. 1, with a cam groove A⁴ shown by dotted lines, and at its right hand side with two cam grooves A⁵, A⁶. The groove A⁴ receives a stud b of an actuator B shown as a lever forked at its upper end to embrace a cross rod b' of a carrying frame or slide B X slidably sustained on rods B' held in ears b² of the framework. The cross rod b' receives upon it loosely the hub of the label fork B³, a spiral spring b³ surrounding said rod and connected at one end therewith and acting at its other end on the fork so sustaining said fork that it will contact yieldingly with the parts now to be described.

The actuator described reciprocates the carrying frame in a right line. The cam groove A⁶ receives a roller or other stud b⁴ at the inner end of a lever C pivot-

ed at C' and connected by a fork at its outer end with a rod C² of a jaw-carrying cross head C³, shown as grooved at its sides to embrace ways C⁴ at the inner sides of the front legs of the framework. The cross head has ears d that receive pivots or studs d' that are embraced by arms d² having irregular cam slots d³ that receive each a roller or other stud d⁴ of stands d⁵ longitudinally adjustable in the frame said stands or brackets being held in their adjusted position by screws 2. The arms d² are provided at their upper ends with flexible wipers d⁶ preferably of india rubber, said wipers being clamped to said arms by plates 3 and screws 3X. These wipers contact with the label after the same has been laid, as will be described, on a bottle D sustained by the bottle rest D', it having a shank D² acted upon by a locking device 4 shown as a screw. The rest may be adjusted vertically according to the diameter of the bottle or other package to which the label is to be applied, and the stands d⁵ may be adjusted to adapt the wipers to the diameter of the bottle or other package. The studs and slots afford means for guiding the wiper carrying arms positively, and insuring the movement of the wipers vertically that the wipers may act upon the bottle to lay the label thereon and the incurved shape given to the lower ends of the slots as the arms are raised serve to spread the upper ends of the arms and move the wipers one away from the other, as represented in Fig. 1, to form a space for the reception of the bottle or other package. It will be noticed that as soon as the cross head C³ starts downwardly, the studs d⁴ act quickly to close the upper ends of the arms, and place the wipers above but in the path of the bottle, so that as the downward motion of the cross head is continued, the wipers strike the bottle above its diameter and are forced yieldingly against the label on the bottle while the wipers pass the bottle, and arrive in the position shown in Fig. 2. The cam slots d³ co-acting with the studs therein perform a very important purpose, that is, they open positively the arms as the cross-head rises, instead of letting the arms drop or move away one from the other through the action of springs, the controlling arms in their positive movements toward and from each other materially adding to the speed of the machine and obviating the shocks due to rapid running.

The labels e in a pile are held between depending arms e' shown as six in number, and as depending from a cross head e² forming part of the label holder. The inner sides of the depending arms near their lower ends have each a suitable projection 6, the series of projections receiving against them the lowermost label of the pile of labels, said projections sustaining the pile of labels between said arms.

The label holder is provided with lateral extensions

7 that enter guide ways 8 in the frame-work, and below said guide ways each extension has a stud 10, see Figs. 3 and 5, Fig. 3 where one of said studs is shown in section, it being supposed to have been cut off from 5 the label holder. This stud is shown in Fig. 3 chiefly to illustrate the engagement therewith of the arms of the rocking frame F to be described; that is used to reciprocate the label holder after the taking of each label therefrom. The upper end of the label holder is 10 provided with a cover e⁶ that receives a notched or screw threaded stem e⁷ that rises from a follower e⁸ that normally acts upon the uppermost label of the pile to keep the pile seated on the projections 6. The label holder also sustains a catch e⁹ pivoted at 10^X and acted 15 upon by a spring 12, the spring serving normally to keep the lower point of the catch, see Fig. 3, in engagement with the notched or screw threaded shank. As the labels are picked off one after the other from 20 the bottom of the pile, the pile decreases in depth and the follower follows down by gravity, but the catch e⁹ prevents the follower from rising when the label holder is lowered to bring its lowermost label in contact with the upper side of the fork B³.

The framework sustains a rod F' that constitutes a 25 fulcrum for the rocking frame F comprising backwardly extended arms f and forwardly extended arms f'. The backwardly extended arms are forked each to fit one of the studs 10 referred to forming part of the label holder, while the forwardly extended arms are 30 also forked to embrace studs 14 one of which is illustrated by dotted lines in Fig. 3, extended from the paste trough E which will be provided with paste, gum, glue or other usual material. The ends f³ of the trough are shaped to enter guide ways of the frame. 35 One of the arms f has joined to it at 15 a link 16, the lower end of which is connected at 17 with a lever 18 connected with a rock shaft 19 supported in a bearing 19^X and provided at the opposite end with an arm 50 having a stud 20 that enters the cam groove A⁵ that 40 moves said rocking frame as the cam rotates so that when the label holder is lowered the paste trough will 45 be elevated, and vice versa.

The paste trough at its front side has two ears g that receive loosely a pin g' with which is attached an arm 45 g², said pin being surrounded by a spring g³ that normally acts to seat the hub of the arm on the lower ear. The end of the arm is slotted to receive an ear g⁴ of a presser g⁵, said ear being slotted as shown in Fig. 3, to embrace a pin g⁶ carried by the arm. The upper 50 side of the arm has attached to it by a suitable screw a spring g⁷ that acts upon the upper end of the ear. The paste trough at its rear side has ears 22 that receive a rod 23 on the opposite ends of which are hung the upper ends of arms 24 slotted at their lower ends, as shown 55 in dotted lines Fig. 3, and full lines, Fig. 3² to receive the shaft 25 of the paste roll f², the periphery of said paste roll entering the paste trough through a slot or throat cut in the same by removing its lower inner corner and a part of its inner side. This paste roll may 60 be ratcheted around or rotated slowly by or through an arm or pawl carrier 26 provided with a pawl 27 that engages the teeth of a ratchet wheel 28 on the shaft 25, said arm being moved intermittently by or through a link 40 jointed at 41 to the actuator B. The shaft 25 65 also has connected with its opposite end a hand-wheel

29 by which the paste wheel may be revolved by hand when necessary. The paste box is also provided with an adjusting device 29^X shown as a screw, see Fig. 4, the inner end of which abuts one of the arms 24, and determines how far the paste roll shall enter the paste 70 box, and also determines the distance between the periphery of the paste roll and the edges of the slot or mouth of the paste box.

By the term paste as herein used with relation to the 75 contents of the so-called paste box, I mean to include any gum, glue, wax or other liquid adapted to be deposited upon the label fork. The paste box herein shown has a mouth, slot or side opening formed in the lower part thereof that receives a paste roller, the journals of which are sustained in arms carried by said 80 paste box, the arms being adjustable to move the paste roller more or less into said mouth, and the inner wall of the paste box above the paste roller is out-turned or provided with a lip, as at 30, and the paste carried by the roller out of the box accumulates at that point. 85

It is desirable in many instances to date the label to show when it was applied to the bottle. To provide for this I have devised a dating mechanism comprising a lever h pivoted at h', the lever having a short arm h² standing substantially at right angles to its long arm. 90 The end of the long arm has a rod h³ that sustains at its upper end any usual form of type or printing device h³X, shown mostly by dotted lines in Fig. 3. The lever H has a standard h⁴ provided at its upper end with an ink-pad h⁵. When the dating device stands in the 95 position shown in Fig. 3, and the wipers are elevated, it will be noticed that the inking device h⁵ meets and applies ink to the type, and it will be understood that as the slide B²X is moved rearwardly, the yoke of the 100 label carrying fork will strike the shorter arm h² of the dating device, and will turn the same so that the printing device of whatever form will strike the unprinted side or underside of the lowermost label of the pile.

Fig. 3 of the drawing shows the yoke F in its horizontal position and at this time it is supposed that the 105 arms d² carrying the wipers are open, as represented in Fig. 1. A bottle will be laid upon the rest D' between the fork of the label sustainer and as the cam wheel is rotated in the direction of the arrow, the lever 18 will be moved to depress the paste-box and its roller, and at 110 the same time the slide frame B²X will be started backwardly causing the roller to contact with the upper sides of the yieldingly sustained fork B³, said fork being drawn over the paste roller. After the upper sides of the paste fork have traveled longitudinally under the 115 paste roller and been provided with paste, the fork finally arrives under the pile of labels held in the label holder and while the label fork provided with paste stands under the pile of labels, the rocking frame F is again moved, this time depressing the label holder and 120 elevating the paste trough and its roller. As the label holder descends the underside of the lowermost label of the pile contacts with the upper side of the paste fork and the label container is lifted sufficiently to enable the lowermost label of the pile then held by the 125 paste upon the fork to be detached, said label being deposited upon the upper side of said fork and being sustained by said fork while the latter is moved forwardly with its label until the fork arrives in the position, Fig. 3. During this movement the rocking frame 130

assumes the central position Fig. 3 with the paste roller in a position to let the fork, it carrying a label, pass thereunder at which time the paste trough and its roller and the frame descend sufficiently to cause the presser 5 to take the label from the fork and apply it to the bottle, and immediately the fork is retracted to be again supplied with paste as described, while the cross head C³ carrying the arms provided with the wipers will descend, said wipers contacting with the outer printed 10 side of the label at each side of the point where the label is first deposited on the bottle or package, thus wiping the pasted label thoroughly on to the bottle or package.

Having fully described my invention what I claim 15 as new and desire to secure by Letters Patent is:—

1. The combination with a paste box open at the junction of its side and bottom, and a paste roller having a portion of its periphery extended into said box through said side opening, of arms sustaining said roller, and 20 means to adjust said arms and roller to thereby regulate the amount of paste taken up by the roller.

2. The combination with a paste box open at the junction of its side and bottom, and a paste roller having a portion of its periphery extended into said box through 25 said side opening, of arms sustaining said roller, and means to adjust said arms and roller to thereby regulate the amount of paste taken up by the roller, and means to rotate said roller in said arms.

3. In apparatus of the class described, a paste box combined with a presser, and means to connect the same yieldingly with the paste box.

4. In apparatus of the class described, a label holder having depending arms provided with projections to sustain the lowermost label of a pile of labels, a paste box 35 having an opening at one side, a paste roller having a portion of its periphery entering said opening, arms connected with said paste box and receiving the journals of said paste roller, means to adjust the arms to cause the roller to enter more or less the box, and a lever connected operatively at its opposite ends with said label holder and paste box, combined with means for moving said label holder and paste box simultaneously in opposite directions, a label fork to which paste is applied upon its upper side from said paste roller said fork receiving thereon and sustaining a label, and means to move said label fork that the pasted label may be taken therefrom and applied to a bottle.

5. In apparatus of the class described, a label holder, means to sustain a pile of labels in said holder, a label 50 fork to receive upon it and sustain the lowermost label in said holder, means to apply paste to the upper side of the label fork, and means thereafter to move the label holder that its lowermost label may be put in contact with said label fork preparatory to the latter removing said label from the pile of labels.

6. In a machine of the class described, a label holder, means to sustain a pile of labels therein, a dating mechanism located below the under side of the pile of labels, a label carrying fork, and means to actuate the same, the 60 latter in its backward movement to pick off a label from the under side of the pile of labels actuating the dating mechanism to date the label before it is taken from the pile.

7. In apparatus of the class described, a label holder, 65 guide rods, a label sustaining fork sliding thereover and adapted to receive upon its upper side a label, combined with a paste box having a paste roller, and means to move said paste box and its roller vertically to apply paste to the upper side of the paste fork preparatory to said fork taking a label from the label holder, and means to move said label holder vertically.

8. In apparatus of the class described, a label fork, a bottle rest, a paste box to apply paste to the upper side of said label fork, and means to move said label fork, 75 combined with a presser yieldingly connected with said paste box and acting upon the upper side of the label sustained by said label fork, and means to move said

paste box and presser vertically that the latter may apply the label to a bottle.

9. In apparatus of the class described, a label holder, 80 a label fork adapted to receive upon its upper side a label, the latter being taken from the bottom of the pile of labels in said label holder, a paste box having a paste roller a part of which is exposed below the box, means to move said box vertically and means to move the label fork under and transversely to the axis of the paste roller said fork in one direction of its movement being supplied with paste from the paste roller, and in the other direction of its movement moving the label sustained on its upper side under said roller but out of contact therewith.

10. In apparatus of the class described, a paste box having a paste roller depending below the bottom thereof, and a presser connected yieldingly with said paste box, combined with a rest for a bottle or package, and a paste 95 fork adapted to receive upon its upper side a label, and means to reciprocate said paste fork as and for the purpose described.

11. In apparatus of the class described, a paste box having a depending paste roller, a label holder, a label fork adapted to receive upon its upper side and sustain a label, means to move the same in plane below the bottom of said paste box and label holder so that said label fork occupies at times a position under the paste box and then under the label holder, and means to move said paste box 100 and label holder simultaneously oppositely vertically as and for the purposes set forth.

12. In apparatus of the class described, a label holder, a rest for a bottle, a paste box having a roller, a label fork, 110 means to move said label fork from its position under the label holder, where it receives a label, into position above the rest containing the bottle to which the label is to be applied, means to lower the paste box and its roller as the label fork is retracted to thus supply paste to said fork, said paste box and roller being raised as the label fork is moved forwardly with a label into position above the rest sustaining said bottle, and means to transfer the label from the label rest on to said bottle.

13. In a machine of the class described, a main shaft, 115 a disk carried thereby provided with a series of cam grooves, a cross head (C³), slotted arms carried thereby, rollers entering the slots of said arm wipers connected with said arms, a lever connected with said cross head and actuated by one of the cam grooves of said disk, a package or bottle sustainer, guide rods, a carrying frame slidably sustained on said rods, a label fork connected with said carrying frame, combined with a lever connected with said carrying frame and actuated by another of the cams of said disk, a label holder, dating mechanism comprising 125 a lever (h) actuated by said carrying frame to date a label before the same is taken from said label holder.

14. In a machine of the class described, a main shaft, 130 a disk carried thereby provided with a series of cam grooves, a cross head (C³), slotted arms carried thereby, rollers entering the slots of said arms wipers connected with said arms, a lever connected with said cross head and actuated by one of the cam grooves of said disk, a package or bottle sustainer, guide rods, a carrying frame slidably sustained on said rods, a label fork connected with said carrying frame, combined with a lever connected with said carrying frame and actuated by another of the cams of said disk, a label holder, dating mechanism comprising 135 a lever (h) actuated by said carrying frame to date a label before the same is taken from said label holder.

15. In apparatus of the class described, guide rods, a slide frame, carried thereby, a label fork connected with said slide frame by a spring, a paste box, a paste roller to 145 apply paste to the upper side of said fork means to raise and lower said paste box and paste roller and to slide said frame and with it the label fork, the latter being adapted to yield slightly when the paste roller is applying paste to its upper side.

16. In a machine of the class described, a label holder, a paste box having a paste roller, a rocking frame having forked ends engaging parts of said paste box and label holder, a lever, and a link connected with said rocking frame, and a cam for moving said lever substantially as 150 described.

17. In apparatus of the class described, a paste box

having an opening cut in one side thereof, the parts of the box at the upper side of said opening having a lip (30), arms connected with said box, a paste roller sustained in said arms, said paste roller entering the side opening in said box, and means to adapt said roller out and in said box, the periphery of the roller depending below the under side of said paste box.

18. In apparatus of the class described, a paste box having an opening cut in one side thereof, the parts of the box at the upper side of said opening having a lip (30), arms connected with said box, a paste roller sustained in said arms, said paste roller entering the side opening in said box, and means to adjust said roller out and in said box, the periphery of the roller depending below the under side of said paste box, a label fork, a slide frame upon which said label fork is pivoted, a spring acting to sustain said label fork on said frame yieldingly, and means to raise and lower said paste box as and for the purpose described.

19. In apparatus of the class described, a paste box

having an opening cut in one side thereof, the parts of the box at the upper side of said opening having a lip (30), arms connected with said box, a paste roller sustained in said arms, said paste roller entering the side opening in said box, and means to adjust said roller out and in said box, the periphery of the roller depending below the under side of said paste box, a label fork, a slide frame upon which said label fork is pivoted, a spring acting to sustain said label fork on said frame yieldingly, and means to raise and lower said paste box as and for the purpose described.

In testimony whereof, I have signed my name to this 30 specification, in the presence of two subscribing witnesses.

Corrections in Letters Patent No. 860,629.

It is hereby certified that Letters Patent No. 860,629, granted July 23, 1907, upon the application of Walter W. Bradbury, of Lawrence, Massachusetts, for an improvement in "Machines for Applying Labels," errors appear in the printed specification requiring correction, as follows: On page 3, line 122, the word "arm" should read *arms*, and on page 4, line 5, the word "adapt" should read *adjust*; and that the said Letters Patent should be read with these corrections therein that the same may conform to the record of the case in the Patent Office.

Signed and sealed this 20th day of August, A. D., 1907.

[SEAL.]

C. C. BILLINGS,
Acting Commissioner of Patents.

having an opening cut in one side thereof, the parts of the box at the upper side of said opening having a lip (30), arms connected with said box, a paste roller sustained in said arms, said paste roller entering the side opening in said box, and means to adapt said roller out and in said box, the periphery of the roller depending below the under side of said paste box.

18. In apparatus of the class described, a paste box having an opening cut in one side thereof, the parts of the box at the upper side of said opening having a lip (30), arms connected with said box, a paste roller sustained in said arms, said paste roller entering the side opening in said box, and means to adjust said roller out and in said box, the periphery of the roller depending below the under side of said paste box, a label fork, a slide frame upon which said label fork is pivoted, a spring acting to sustain said label fork on said frame yieldingly, and means to raise and lower said paste box as and for the purpose described.
19. In apparatus of the class described, a paste box

having an opening cut in one side thereof, the parts of the box at the upper side of said opening having a lip (30), arms connected with said box, a paste roller sustained in said arms, said paste roller entering the side opening in said box, and means to adjust said roller out and in said box, the periphery of the roller depending below the under side of said paste box, a label fork, a slide frame upon which said label fork is pivoted, a spring acting to sustain said label fork on said frame yieldingly, and means to raise and lower said paste box as and for the purpose described.

In testimony whereof, I have signed my name to this specification, in the presence of two subscribing witnesses.
